UNITED STATES PATENT OFFICE.

ARTHUR C. VICARY, OF ERIE, PENNSYLVANIA, ASSIGNOR, BY DIRECT AND MESNE ASSIGNMENTS, TO ERIE STEAM SHOVEL COMPANY, OF ERIE, PENNSYLVANIA, A CORPORATION OF PENNSYLVANIA.

POWER EXCAVATING MACHINE AND METHOD OF ACTUATING THE SAME.

Application filed February 23, 1923. Serial No. 620,727.

To all whom it may concern:

Be it known that I, ARTHUR C. VICARY, a citizen of the United States, residing at Erie, in the county of Erie and State of Pennsylvania, have invented new and useful Improvements in Power Excavating Machines and Methods of Actuating the Same, of which the following is a specification.

10 Steam shovels and cranes as heretofore made have been usually driven by steam engines although such apparatus has been driven electrically and by means of explosive engines. Such apparatuses are very often used in cities and in other locations where the smoke and other inconveniences incident to the steam engine make it very undesirable but owing to its greater flexibility of power particularly on certain parts 20 of the apparatus it has been used to a very much greater extent even in such locations than any other type of apparatus. Neither the electric nor the explosive engine machines when acting directly on all parts of 25 the machine are well suited for the purpose because of lack of flexibility or acceleration. This is particularly true of the turning and crowding engines on steam shovels which are subjected to very severe strains 30 and if capacity is to be gained must be subjected to very rapid action and must be subject to a very nice control so that the operator may adjust these parts both as to the material which is being moved and as to 35 the wagon or other receptacle to which the material is carried.

I have succeeded in forming a method and an apparatus in which the good features of the different kinds of power are successfully utilized without the attending disadvantages. In the preferred form of apparatus and as shown I utilize an explosive engine which drives the hoisting drum and supplies the traction effort of the machine. This is clutch controlled. This power satisfies the requirements as to the hoisting apparatus with reasonable efficiency and without great inconvenience. I preferably utilize this same internal combustion engine to operate a compressor by means of which the air is compressed and forms the driving medium for the crowding engine and turning engine so that these engines are fluid actuated and have the flexibility and capacity and

ease of control desirable for these functions. 55 With this engine which is operated continuously a comparatively small compressor will supply the air for the intermittent operation of the turning and crowding engines. 60

In the accompanying drawings I have exemplified an apparatus carrying out my invention as follows:—

Fig. 1 shows a plan view of the shovel platform showing the arrangement of power 65 and controlling devices thereon.

Fig. 2 a side elevation of a power shovel. 1 marks the shovel frame. This is carried by a steering axle 2 and driving axle 3 in the usual manner. A revolving platform 70 4 is pivoted at 5 on the turn table 6. A boom 8 extends from the revolving platform in the usual manner and a dipper stick 9 is mounted on the boom and carries a dipper 10. The dipper stick has a rack 11 which meshes with a gear 12. The gear 12 is fixed on a shaft 13. A gear 14 is fixed on the shaft 13 and a gear 15 mounted on the engine shaft 16 meshes with the gear 14. The engine shaft 16 forms a part of the crowding engine 17 mounted on the boom 8, this crowding engine being of ordinary construction as used in some power shovels.

A hoisting line 18 extends from a drum 18^a on the platform over sheaves 19 through 85 the sheaves 20 on the dipper and operates in the usual manner. A turning gear 22 is mounted on the frame and a pinion 23 operates in this gear. The pinion is carried by a shaft 24. A gear 25 is mounted on the shaft 24 and meshes with a gear 26. The gear 26 is mounted on a shaft 27. A beveled gear 28 is mounted on the upper end of the shaft 27 and meshes with a pinion 29. The pinion 29 is mounted on the engine shaft 95 of a turning engine 30. This turning engine is a pressure fluid actuated engine, the ordinary steam engine of a steam power shovel answering the purpose admirably.

The traction driving mechanism of the 100 shovel is of ordinary construction having a beveled gear 31 mounted on the axle 3. The beveled gear 31 meshes with a gear 32. The gear 32 is mounted on a shaft 33. A gear 34 is also mounted on the shaft 33 and meshes with a beveled gear 35. The beveled gear 35 is mounted on a shaft 36 extending upwardly through the axis of the platform.

A gear 37 is mounted on the upper end of the shaft 36 and meshes with a beveled gear 38. The beveled gear 38 is carried by a shaft mounted in bearings 38^a and a gear 38^b is fixed on the same shaft meshing with a gear 39. The gear 39 is mounted on a drum shaft 40. A gear 41 is also mounted on the drum shaft and meshes with a pinion 42. The pinion 42 is mounted on a shaft 43 and is driven from a belt pulley 44. A belt 45 extends from the pulley 44 to a drive pulley 46 on the engine shaft of the explosive engine 47. This explosive engine is of the ordinary stationary high duty explosive type controlled by any suitable governor as 46^a. A compressor 47^a has a drive pulley 48 mounted on an engine shaft 49 and this is driven by a belt 49^a running from the drive pulley 49^b on the explosive engine shaft. The compressor has the compressor cylinders 50 having the discharge pipe 51 from the high pressure cylinder leading to the receiver 52. A supply pipe 53 extends from the receiver and a branch pipe 54 extends from the supply pipe to the turning engine 30. A branch pipe 55 extends from the pipe 53 to the crowding engine 17. A crowding engine control lever 56 is mounted on a shaft 57. A lever 58 is also fixed on this shaft and a link 59 connects the lever 58 with a valve control lever 60. The valve control lever controlling the valve of the crowding engine 17 in the usual manner. A turning engine control lever 61 is mounted on a shaft 62. A lever 63 is also mounted on this shaft. A link 64 connects the lever 63 with a lever 65, the lever 65 being the control lever for the valve of the turning engine and operating that valve in the usual manner of engines of this type.

A control lever 66 is provided for handling the hoisting drum. This lever is connected by a link 67 with one arm 68 of a bell crank lever, the opposite arm of the lever 69 being connected to a movable element 70 of a clutch 71, the clutch being adapted to lock the shaft 43 with the pulley to connect and release the shaft 43 with the drive pulley 44.

A clutch 72 is provided on the shaft 40 by means of which the gearing 39 may be connected, or disconnected from the hoisting shaft 40 so as to drive the traction gearing. With this construction it will be seen a power apparatus free from smoke or objectionable features so far as its use is concerned is provided and one free from the inconvenience of operating with steam in isolated localities is also obviated in which the flexibility of a fluid-actuated engine is fully utilized and a power element provided suitable for the hoisting engine and traction engine. The intermittent action of the turning and crowding engines requiring a large expenditure of power momentarily with

great acceleration is provided for in a comparatively small power unit.

We use the term fluid pressure actuated engine as designating one in which the pressure fluid is created externally of the engine itself and in which this fluid is introduced into the engine under pressure and actuates the engine through the expansion of said fluid, and we use the term non-fluid pressure actuated engine as one having its energy created within the engine as with an internal combustion engine, or one in which the energy is conveyed to the engine or motor through other agencies than fluid under pressure as with an electric motor.

What I claim as new is:—

1. In a power excavating machine, the combination of a rotating platform, a direct driven rotative hoisting mechanism comprising a non-fluid pressure actuated motor, and an indirectly driven turning mechanism comprising a compressor and a fluid pressure actuated rotatively acting turning engine receiving its fluid from the compressor.

2. In a power excavating machine, the combination of a rotating platform; a fluid pressure actuated turning engine for the platform; a hoist; a non-fluid pressure actuated motor actuating the hoist; and a compressor actuated by the non-fluid actuated motor compressing the fluid for the turning engine.

3. In a power excavating machine, the combination of a rotating platform, a direct driven rotative hoisting mechanism comprising an internal combustion engine, and an indirectly driven turning mechanism comprising a compressor and a fluid pressure actuated rotatively acting turning engine receiving its fluid from the compressor.

4. In a power excavating machine, the combination of a rotating platform, a direct driven rotative hoisting mechanism comprising an internal combustion engine and a clutch control for the hoist, and an indirectly driven turning mechanism comprising a compressor and a fluid pressure actuated rotatively acting turning engine receiving its fluid from the compressor.

5. In a power excavating machine, the combination of a rotating platform; a fluid pressure actuated turning engine for the platform; a hoist; an internal combustion engine actuating the hoist; and a compressor actuated by the internal combustion engine compressing the fluid for the turning engine.

6. In a power shovel, the combination of a dipper, a dipper stick, a direct driven rotative hoisting mechanism comprising a non-fluid pressure actuated motor, and a crowding mechanism comprising a compressor and a fluid pressure actuated crowding engine receiving its fluid from the compressor.

7. In a power shovel, the combination of

- a dipper; a dipper stick; a fluid pressure actuated crowding engine actuating the dipper stick; a hoist; a non-fluid pressure actuated motor actuating the hoist; and a 60 compressor actuated by the motor compressing the actuating fluid for the crowding engine.
8. In a power shovel, the combination of a dipper; a dipper stick; a fluid pressure actuated crowding engine actuating the dipper stick; a hoist; and internal combustion engine actuating the hoist; and a compressor actuated by the internal combustion engine compressing the fluid for the crowding 70 engine.
9. In a power shovel, the combination of a dipper; a dipper stick; a fluid pressure actuated crowding engine actuating the dipper stick; a hoist; an internal combustion engine actuating the hoist; a compressor actuated by the internal combustion engine compressing the fluid for the crowding engine; and a clutch control for the hoist.
10. In a power shovel, the combination of a dipper; a dipper stick; a fluid pressure actuated crowding engine actuating the dipper stick; a turning platform on which the dipper stick is mounted; a fluid pressure actuated turning engine turning the platform; a hoist; a non-fluid pressure actuated motor actuating the hoist; and a compressor actuated by the motor compressing fluid for the crowding and turning engines.
11. In a power shovel, the combination of a dipper; a dipper stick; a fluid pressure actuated crowding engine actuating the dipper stick; a turning platform on which the dipper stick is mounted; a fluid pressure actuated turning engine turning the platform; a hoist; an internal combustion engine actuating the hoist; and a compressor actuated by the internal combustion engine and compressing fluid for the crowding and turning engines.
12. In a power shovel, the combination of a dipper; a dipper stick; a fluid pressure actuated crowding engine actuating the dipper stick; a turning platform on which the dipper stick is mounted; a fluid pressure actuated turning engine turning the platform; a hoist; an internal combustion engine actuating the hoist; a compressor actuated by the internal combustion engine and compressing fluid for the crowding and turning engines; and a clutch control for the hoist.
13. In a power excavating machine, the combination of a rotative platform; a fluid pressure actuated turning engine for the platform; a hoist; a non-fluid pressure actuated motor actuating the hoist; a traction gearing for the machine; and a connection between the non-fluid actuated motor and the traction gearing.
14. In a power excavating machine, the combination of a rotative platform; a fluid pressure actuated turning engine for the platform; a hoist; a non-fluid pressure actuated motor actuating the hoist; a traction gearing for the machine; a connection between the non-fluid actuated motor and the traction gearing; and a compressor driven by the motor compressing actuating fluid for the turning engine.
15. In a power shovel, the combination of a dipper; a dipper stick; a fluid pressure actuated crowding engine for the dipper stick; a hoist; a non-fluid actuated motor actuating the hoist; a traction gearing driven from the motor; and a compressor driven by the motor and supplying actuating fluid for the crowding engine.
16. The method of actuating power excavating machines which consists in delivering power from a power source, utilizing the power from the source for directly actuating a hoist, and utilizing the power from the source indirectly through a fluid pressure actuated motor having its actuating fluid supplied from the power derived from the source to give turning movement to the machine.
17. The method of actuating power excavating machines which consists in delivering power from a power source, utilizing the power from the source for directly actuating a hoist, and utilizing the power from the source indirectly through a fluid pressure actuated motor having its actuating fluid supplied from the power derived from the source to give crowding movement to a digging implement actuated by the hoist.
18. The method of actuating power excavating machines which consists in delivering power from a power source, utilizing the power from the source for directly actuating a hoist, and utilizing the power from the source indirectly through fluid pressure actuated motors having their actuating fluid supplied from the power derived from the source to give crowding movement to an implement actuated by the hoist and turning movement to the machine.
19. The method of actuating power excavating machines which consists in generating the power therefor by a continuously operating explosive engine, utilizing the power from the engine for directly actuating the hoist and utilizing the power from the engine indirectly through a fluid pressure actuated motor having its actuating fluid supplied from power derived from the engine to give turning movement to the machine.
20. The method of actuating power excavating machines which consists in generating the power therefor by a continuously operating explosive engine, utilizing the power from the engine for directly actuating the hoist and utilizing the power from the engine to give turning movement to the machine.

5   gine indirectly through a fluid pressure actuated motor having its actuating fluid supplied from power derived from the engine to give crowding movement to a digging implement actuated by the hoist.

10   21. The method of actuating power excavating machines which consists in generating the power therefor by a continuously operating explosive engine, utilizing the power from the engine for directly actuating the hoist and utilizing the power from the engine indirectly through fluid pressure actuated motors having their actuating fluid supplied from power derived from the engine 15 to an implement actuated by the hoist and turning movement to the machine.

20   22. In a machine, the combination of a plurality of instrumentalities having intermittent and successive operation; a primary motor operating directly on one of said instrumentalities; a secondary motor operating on the second of said instrumentalities; and an energy storing means supplied from the primary motor and supplying energy to the secondary motor.

25   23. In a machine, the combination of two instrumentalities operating intermittently and successively; a primary motor directly actuating one of said instrumentalities; a fluid actuated secondary motor actuating the other of said instrumentalities; and a compressor driven by the primary motor and compressing fluid for actuating the secondary motor.

30   24. In a power excavating machine, the combination of a digging implement; a primary motor operating directly on said digging instrument; a secondary motor operating on said implement; and energy storing means actuated by the primary motor and delivering energy to the secondary motor.

35   25. In a power excavating machine, the combination of a digging implement; a primary motor acting directly on the implement; a fluid pressure actuated secondary motor acting on the implement; and a compressor compressing fluid for actuating the secondary motor driven by the primary motor.

40   26. In a power excavating machine, the combination of a digging implement; a hoisting device for the implement; a primary motor operating directly on the hoisting device; a secondary motor acting on the implement; and energy storing means supplied from the primary motor and supplying energy to the secondary motor.

45   27. In a machine, the combination of a plurality of instrumentalities having intermittent and successive operation; an internal combustion engine acting as a primary motor operating directly on one of said instrumentalities; a secondary motor operating on the second of said instrumentalities; and an energy storing means supplied from

the primary motor and supplying energy to the secondary motor.

50   28. In a machine, the combination of two instrumentalities operating intermittently and successively; an internal combustion engine acting as a primary motor directly actuating one of said instrumentalities; a fluid actuated secondary motor actuating the other of said instrumentalities; and a compressor driven by the primary motor and compressing fluid for actuating the secondary motor.

55   29. In a power excavating machine, the combination of a digging implement; an internal combustion engine acting as a primary motor operating directly on said digging implement; a secondary motor operating on said implement; and energy storing means actuated by the primary motor and delivering energy to the secondary motor.

60   30. In a power excavating machine, the combination of a digging implement; an internal combustion engine acting as a primary motor operating directly on the implement; a fluid pressure actuated secondary motor acting on the implement; and a compressor compressing fluid for actuating the secondary motor driven by the primary motor.

65   31. The method of actuating power excavating machines which consists in giving a power impulse to a digging implement of said machine directly from a primary motor, storing energy from the primary motor, and delivering the energy so stored to the digging implement through a secondary motor.

70   32. The method of operating a power excavating machine having a digging instrumentality which consists in directly delivering energy to the instrumentality from an internal combustion motor, storing energy from the motor, and delivering the energy so stored to a secondary motor operating on the digging instrumentality.

75   33. The method of operating a power excavating machine having a digging instrumentality which consists in directly delivering energy to the instrumentality from a primary motor, compressing fluid by energy from the primary motor, and operating the instrumentality through a fluid pressure actuated motor from the fluid compressed.

80   34. The method of actuating a power excavating machine having a digging instrumentality which consists in delivering power directly to the instrumentality from an internal combustion engine, compressing fluid by energy from the engine, and operating the instrumentality by a fluid actuated motor actuated by the fluid compressed.

85   In testimony whereof I have hereunto set my hand.

ARTHUR C. VICARY.
